CLAIM

The ornamental design for a cover for camera, as shown and described.

DESCRIPTION

FIG. 1 is a front, right and top perspective view of a cover for camera showing our new design;

FIG. 2 is a front view thereof;

FIG. 3 is a rear view thereof;

FIG. 4 is a left side elevation view thereof;

FIG. 5 is a right side elevation view thereof;

FIG. 6 is a top view thereof;

FIG. 7 is a bottom view thereof;

FIG. 8 is a rear, right and top perspective view thereof; and,

FIG. 9 is a front, right and top perspective view thereof in an environment of use.

The broken lines in FIGS. 1-8 illustrate portions of the cover for camera that form no part of the claimed design.

The broken lines illustrating portions of a camera in FIG. 9 depict environmental subject matter and form no part of the claimed design.
